WELL BIT

Alfred C. Catland, Alhambra, Calif., assignor to
Globe Oil Tools Company, Los Nietos, Calif.,
a corporation of California

Original application June 22, 1938, Serial No.
215,145. Divided and this application November
18, 1938, Serial No. 241,206

7 Claims. (Cl. 255—71)

This invention relates to well drilling tools and relates more particularly to a bit for use in the rotary method of well drilling. A general object of this invention is to provide a practical, dependable rock bit.

This application is a division of application Serial No. 215,145, entitled "Rock bit", filed June 22, 1938.

Another object of this invention is to provide a rock bit that is of simplified construction and that is inexpensive to manufacture.

Another object of this invention is to provide a rock bit embodying a simple, continuous one-piece bearing member for each set of inner cutters. The continuous one-piece bearing members embodied in the bit of the present invention replace the pluralities of bearing members heretofore employed, thereby increasing the strength of the bit structure and promoting economy in the manufacture of the bit.

Another object of this invention is to provide a well bit of the character mentioned embodying a central web that is formed independently of the body and secured to the body at the time of mounting of the cutters, thereby simplifying the machine work on the body, permitting the use of one-piece bearings for the sets of inner cutters, and providing for the arrangement of the innermost cutters in adjacent relation whereby they may surround boss parts on the web.

The various objects and features of my invention will be fully understood from the following detailed description of a typical preferred form and application of the invention, throughout which description reference is made to the accompanying drawings, in which:

Fig. 1 is a side elevation of the improved bit of this invention. Fig. 2 is an enlarged vertical detailed sectional view of one of the cutters and its bearing means being a view taken as indicated by line 2—2 on Fig. 4. Fig. 3 is a central vertical detailed sectional view of the lower portion of the bit illustrating the mountings for the inner cutters and Fig. 4 is an enlarged fragmentary vertical detailed sectional view of certain of the inner cutters and the adjacent parts.

The well bit of the present invention may be said to comprise, generally, a body 10, a central bridge or web 11 secured to the body 10, outer roller cutters 12, sets or pairs of inner cutters 14 and 15 and means 16 for rotatably supporting the sets of cutters 14 and 15.

The bit body 10 is adapted to be connected with the lower end of a rotary well drilling string. Means is provided on the body 10 for

facilitating its connection with the drilling string. In the construction illustrated a tapered screw threaded pin 17 is provided on the upper end of the body 10 for connecting the body with the drilling string. A pair of diametrically opposite legs 18 is provided on the lower end of the body 10. The legs 18 project downwardly and outwardly from the body 10. A second pair of legs 20 is provided on the body 10. The legs 20 are diametrically opposite and are equally spaced between the legs 18. In the preferred construction the legs 20 project downwardly and outwardly from the lower end of the body 10 and the lower portions of the legs 20 are substantially vertical. The vertical lower parts of the legs 20 have flat substantially vertical inner surfaces or inner sides 22. The legs 18 and 20 are formed integral with the body. A central vertical fluid passage 23 enters the body 10 from the upper end of its pin 17 and ports 24 join the lower end of the passage 23 and serve to discharge the circulation fluid from the lower end of the body. Beans or nozzles 25 may be provided in the ports 24 to direct the fluid downwardly against the cutters 12, 14 and 15.

The bridge or web 11 is secured to the lower end of the body 10 to assist in supporting the cutters 12, 14 and 15 and their respective bearing means. The web 11 is an integral member formed separately or independently of the body 10. The web 11 includes a central vertical part 26 and side parts 27 disposed transversely of and extending along the opposite edges of the part 26. The upper end of the web 11 is flat and opposes a flat downwardly facing surface 28 on the lower end of the body 18. In accordance with the invention the upper end of the web 11 is joined to the body surface 28 by welding 29. The sides of the web part 26 oppose the inner sides 22 of the legs 20. In accordance with the invention cylindrical bosses 30 are provided on the opposite sides of the web part 26 and project toward the opposing legs 20. The lower end of the web 11 is in substantially the same horizontal plane as the lower ends of the body legs 18 and 20.

The web 11 being a simple, separately formed member is inexpensive and easily machined. The web bosses 30 and the several surfaces of the web 11 are exposed and freely accessible prior to the attachment of the web to the body 10. Further the inner sides of the body legs 18 and 20 and the other internal surfaces of the body are accessible for easy machining before the attachment of the web 11 to the body.

The outer cutters 12 are provided to cut the well bore to gauge. As illustrated in the drawings the cutters 12 are frusto-conical members rotatably supported between the body legs 18 and 5 the opposing web parts 27. Suitable peripheral cutting teeth 32 are provided on the outer cutters 12. The means for rotatably supporting the outer cutters 12 form a portion of the subject matter of my co-pending application, referred to above.

10 The cutters 14 and 15 are provided to act on the earth formation at the inner portion of the well bore. The cutters 14 may be termed inner cutters and the cutters 15 may be termed center cutters. The inner and center cutters 14 and 15 15 are provided in sets or pairs positioned at opposite sides of the central vertical axis of the bit and each pair includes a cutter 14 and a cutter 15. The inner cutters 15 are frusto-conical members having tapered or pitched peripheries and flat 20 generally parallel ends. Central longitudinal openings 48 extend through the cutters 14. The openings 48 are of substantial diameter and the inner portions of the openings 48 are somewhat reduced in diameter. The cutters 14 are provided with suitable peripheral cutting teeth 49. The inner cutters 14 are positioned to have their large ends facing outwardly.

The center cutters 15 are located at the inner ends of the cutters 14 and are in co-axial relation 30 to the inner cutters. The cutters 15 are cylindrical and are smaller in diameter than the cutters 14. Suitable peripheral cutting teeth 50 are provided on the center cutters 15. Central longitudinal openings 51 extend through the cutters 35 15. The openings 51 are of the same diameter as the reduced inner portions of the openings 48 in the cutters 14. The openings 51 receive the web bosses 30 with slight clearance. In the preferred construction annular flanges or shoulders 40 52 are provided at the bases of the bosses 30 and are received in counterbores in the inner ends of the openings 51. The shoulders 52 assist in preventing the entrance of mud and cuttings at the openings 51.

45 The means 16 for rotatably mounting the pairs of inner and center cutters 14 and 15 includes a single tubular bushing or bearing member 53 for each pair of cutters 14 and 15. The bearing members 53 extend through the openings 48 and 50 51 of the cutters 14 and 15, respectively, with suitable clearance having reduced inner portions received in the reduced inner parts of the openings 48 and in the openings 51. The inner ends of the bearing members 53 engage against the bosses 30 and the outer ends of the bearing members engage against the inner sides 22 of the body legs 20. Radial flanges 54 are provided on the outer ends of the bearing members 53. The flanges 54 overlap substantial portions of the 60 outer ends of the cutters 14 and are preferably partially inset or recessed in the ends of the cutters. The flanges 54 aid in preventing the entrance of mud and cuttings to the cutter openings 48. Lugs 55 are provided on the flanges 54 and welds 56 secure the lugs 55 to the lower ends of the legs 20. The lugs 55 are formed to engage upwardly against the lower ends of the legs 20 and this engagement, together with the welds 56, prevents rotation of the bearing members 53. The bearing members 53 being welded to the body legs 20 are effectively held against vibration.

75 The means 16 is in the nature of an anti-friction bearing means operating to support the cutters 14 and 15 with a minimum of friction. A

plurality of spaced annular ball grooves 56 is provided in the wall of the opening 48 in each cutter 14. Circumferentially spaced ball grooves 57 are provided in the bearing members 53 to oppose the grooves 56. In the form of the invention illustrated there are three sets or pairs of opposing grooves 56 and 57 for each cutter 14. Balls 58 are arranged in the opposing grooves 56 and 57 to rotatably support the cutters 14 on the bearing members 53. The grooves 56 and 57 are of such depth that the balls 58 transmit end thrusts in both directions as well as radial thrusts.

10 A pair of spaced annular ball grooves 59 is provided in the wall of the opening 51 of each cutter 15. A groove 60 is provided in each bearing member 53 to oppose the innermost groove 59 in the surrounding cutter 15. The grooves 60 are at the inner ends of the members 53 and have their inner sides open, as illustrated in Figs. 3 and 4 of the drawings. Annular ball grooves 61 are provided in the bearing members 53 to oppose the other grooves 59 in the cutters 15. Series of balls 62 are arranged in the opposing races or grooves 59 and 60 and 59 and 61 to rotatably support the cutters 15 on the bearing members 51. The opposing grooves 59 and 61 are of such depth that the balls 62 received in them are adapted to transmit end thrusts in both directions as well as the radial thrusts. The balls 62 in the grooves 59 and 60 are capable of transmitting outward 30 end thrusts as well as radial thrusts. The corners of the bosses 30 may be ground off or cut away to have suitable clearance with the balls 62 engaged in the opposing grooves 59 and 60. The grooves 60 being open at the inner ends of the bearing members 53 allow the easy arrangement of the balls 62 in the opposing grooves 59 and 60 when the parts are assembled.

35 Radial bores or openings 63 are provided in the bearing members 53 and extend inwardly from their ball grooves 57 to the openings 48. The openings 63 pass or admit the balls 58 to the registering grooves 56 and 57 when the cutters 14 are assembled on the bearing members 53. Plugs 64 occupy the openings 63 to prevent the escape of the balls 58 and the outer ends of the plugs 64 are shaped to conform with the walls of the grooves 57. A radial opening 75 is provided in each bearing member 53 to communicate with its groove 61. The openings 75 pass or 40 admit the balls 62 to the opposing grooves 59 and 61 when the cutters 15 are assembled on the bearing members 53. Plugs 65 occupy the openings 75 and the outer ends of the plugs 65 are shaped to conform with the walls of the 45 grooves 61.

50 Means are provided for preventing turning and outward movement of the plugs 64 and 65. An internal longitudinal key-way 66 is provided in each bearing member 53 and intersects the inner ends of the openings 63 and 75. Keys 67 are provided on the inner ends of the plugs 64 and cooperate with the key-ways 66. Similar keys 68 are formed on the inner ends of the plugs 65 and cooperate with the key-ways 66. The keys 67 55 and 68 are engaged in the key-ways 66 to prevent turning and outward movement of their respective plugs 64 and 65. The inner cutters 14 and the center cutters 15 are supported by the above described ball bearing means in such a 60 manner that thrust washers are unnecessary and the adjacent cutters are at all times free of one another.

65 The cutter mounting means 16 further includes a single supporting pin or shaft 70 for carrying 70

the two bearing members 53. Horizontal or transverse openings 71 are provided in the two body legs 20 and a transverse opening 72 is provided in the web part 26 in axial alignment with the openings 71. The shaft 70 is arranged through or carried in the aligned openings 71 and 72. The shaft 70 extends through the tubular bearing members 53 to support the same. One end portion of the shaft 70 is threaded in one opening 71 and a head 73 is formed on the other end of the shaft and is received in the other opening 71. It will be apparent how the single pin or shaft 70 serves to support two cutter units or assemblies comprising the bearing members 53 and the cutters 14 and 15. The opening 72 in the web part 26 is co-axial with the bosses 30 and extends through the bosses to be of substantial length and to provide a maximum support for the intermediate portion of the shaft 70. The pin or shaft 70 cooperates with the inner ends of the plugs 64 and 65 to prevent inward movement of the plugs. In the preferred construction the bearing members 53 are formed and mounted so that the openings 63 and 75 are in their upper 25 sides or portions. With this relationship of parts the walls of the grooves 57 and 61 at the openings 63 and 75 and the end parts of the plugs 64 and 65 are relieved of the heavier drilling forces.

The means 16 just described supports the inner 30 cutters 14 for rotation about a horizontal axis and to project downwardly beyond the lower ends of the body legs 20 so that they act on the formation at the bottom of the well bore. The center cutters 15 are supported by the means 16 to rotate about 35 a transverse or horizontal axis and to project downwardly beyond the lower end of the web 11 to cut the central or inner part of the well bore.

It is believed that the operation of the bit provided by this invention will be readily understood 40 from the foregoing detailed description. In operation the bit body 10 is secured to the lower end of a well drilling string and the string is rotated and fed downwardly in the usual manner. Circulation fluid is pumped down through the drilling 45 string to discharge from the nozzles 25. This fluid flushes the cutters 12, 14 and 15 and maintains the necessary turbulence in the bottom of the well. The outer roller cutters 12 projecting downwardly beyond the body legs 18 cut the well 50 bore to gauge and make an annular cut in the bottom of the well. The sets or pairs of inner cutters 14 and center cutters 15 act on the bottom wall of the well bore to drill the inner portion of the well.

The cutters of the bit are supported by dependable anti-friction bearing means to rotate independently and with a minimum of friction. It is to be observed that the cutters are supported solely by balls and that thrust washers and roller 60 cutters are not employed. Each pair of inner and center cutters 14 and 15 is supported on a single integral bearing member 53. The members 53 being integral are strong and durable and are not subject to vibration.

Having described only a typical preferred form and application of my invention, I do not wish to be limited or restricted to the specific details herein set forth, but wish to reserve to myself any variations or modifications that may appear to those skilled in the art or fall within the scope of the following claims:

Having described my invention, I claim:

1. In a rock bit, a body having a pair of depending legs, a web on the lower end of the body between the legs, aligned transverse open-

ings in the legs and web, a supporting shaft carried in said openings, a tubular bearing member on the shaft at each side of the web and engaged between the web and the opposing leg, sets of roller cutters at opposite sides of the web, and anti-friction bearing means rotatably supporting a set of cutters on each member. 5

2. In a rock bit, a body having a pair of depending legs, a web on the lower end of the body between the legs, aligned transverse openings in the legs and web, a supporting shaft carried in said openings, a tubular bearing member on the shaft at each side of the web and engaged between the web and the opposing leg, sets of roller cutters at the opposite sides of the web, the members each having spaced annular ball grooves and the cutters having ball grooves opposing those in the bearing members, and balls in the opposing grooves rotatably supporting the cutters on the bearing members. 10

3. In a well bit, a body having spaced legs on its lower end, a web at the lower end of the body spaced between the legs, welding joining the web with the body, bosses on the web projecting toward the legs, the legs and web having aligned openings, the opening in the web passing through the bosses, a shaft extending between the legs and supported in said openings, bearing members on the shaft at each side of the web engaged between the bosses and the legs, and sets of roller cutters 15 rotatably supported on each bearing member, one cutter of each set surrounding one of the bosses. 20

4. In a well bit, a body having spaced legs on its lower end, a web at the lower end of the body spaced between the legs, welding joining the web with the body, bosses on the web projecting toward the legs, the legs and web having aligned openings, the opening in the web passing through the bosses, a shaft extending between the legs and supported in said openings, bearing members on the shaft at each side of the web engaged between the bosses and the legs, flanges on the outer ends of the bearing members bearing against the legs, and sets of tubular cutters rotatable on each member, the inner cutter of each set receiving a boss 30 which closes the cutter against the entrance of foreign matter, the outer cutter of each set receiving a flange which closes the cutter against the entrance of foreign matter. 35

5. In a well bit, a body having spaced legs on its lower end, a web at the lower end of the body spaced between the legs, welding joining the web with the body, bosses on the web projecting toward the legs, the legs and web having aligned openings, the opening in the web passing through the bosses, a shaft extending between the legs and supported in said openings, bearing members on the shaft at each side of the web engaged between the bosses and the legs, flanges on the outer ends of the bearing members bearing against the legs, 40 welding securing the flanges to the legs, and sets of tubular cutters rotatable on each member, the inner cutter of each set receiving a boss which closes the cutter against the entrance of foreign matter, the outer cutter of each set receiving a flange which closes the cutter against the entrance of foreign matter. 45

6. In a well bit, a body having spaced legs on its lower end, a web at the lower end of the body spaced between the legs, welding joining the web 50 with the body, bosses on the web projecting toward the legs, the legs and web having aligned openings, the opening in the web passing through the bosses, a shaft extending between the legs and supported in said openings, bearing members on 55

the shaft at each side of the web engaged between the bosses and the legs, the bearing members being integral and continuous from the bosses to the legs, and sets of roller cutters rotatably supported on each bearing member, one cutter of each set surrounding one of the bosses.

7. In a well bit, a body having spaced legs on its lower end, a web at the lower end of the body spaced between the legs, welding joining the web with the body, bosses on the web projecting toward the legs, the legs and web having aligned open-

ings, the opening in the web passing through the bosses, a shaft extending between the legs and supported in said openings, bearing members on the shaft at each side of the web engaged between the bosses and the legs, the bearing members being integral and continuous from the bosses to the legs, a set of cutters arranged in end to end relation on each bearing member, and anti-friction bearing elements supporting the cutters on the bearing elements for free rotation.

5

ALFRED C. CATLAND.
